UNITED STATES PATENT OFFICE.

HENRY A. HAYDEN, OF WESTFIELD, NEW JERSEY, ASSIGNOR TO HAYDEN INVENTIONS CORPORATION, OF WESTFIELD, NEW JERSEY, A CORPORATION OF NEW JERSEY.

BRUSH.

1,313,185.

Specification of Letters Patent. Patented Aug. 12, 1919.

Application filed August 31, 1918. Serial No. 252,135.

To all whom it may concern:

Be it known that I, HENRY A. HAYDEN, a citizen of the U. S., and a resident of Westfield, Union county, New Jersey, have made 5 a certain new and useful Invention in Brushes, of which the following is a specification.

This invention relates to improvements in 10 brushes; the advantages of which improvements, mainly resident in an inclined reversible handle and a plurality of spread-increasing tufts auxiliary to the tufts usually present, will appear hereinafter.

The invention, especially at the present 15 time, when broom-corn is very scarce and thrifty householders must pay high prices for skimpy and short-lived house-brooms; is most advantageously embodied as a substitute for such brooms. In this connection, 20 it is admitted that many attempts have been made to devise a substitute of this kind; but it is a fact, so far as I am aware, that none of these attempts have been successful in 25 the way of providing a really workable and satisfactory broom in which, instead of the long and brittle corn wisps, bristles of shorter and tougher character are used, such as tampico or the like, especially the former, since it is cheap, abundant, very durable, 30 and exceedingly tenacious of the slight degree of elasticity by which it is characterized.

As an embodiment of the invention, then, 35 (but one nevertheless merely illustrative, since the new brush will obviously have many other valuable adaptations, as for a dust-lifting, paint, varnish, whitewash, bill-posting or other brush for floor, ceiling or wall use), the drawings show, and there 40 will be described, a construction affording a house or floor broom, which, despite its cheap cost and the avoidance of the use of expensive and scarce broom-corn, has been found to serve the purpose satisfactorily in 45 practice.

In the drawings,

Figure 1 is a side elevation of the brush, showing the reversible feature of the handle in dotted lines;

50 Fig. 2 is an end elevation of the brush of Fig. 1, one of the parts being broken away and the bristles being indicated by dot-and-dash lines;

Fig. 3 is a section on line 3—3 of Fig. 1, 55 looking in either direction;

Fig. 4 is a perspective view, on an enlarged scale, showing the locking piece of Fig. 1 for securing the handle in either of its reversed positions on the brush-proper;

Fig. 5 is a fragmentary view, similar to 60 Fig. 1, showing a modification, some of the parts being broken away to aid the disclosure;

Fig. 6 is a section on line 6—6 of Fig. 5; and

Fig. 7 is a section on line 7—7 of Fig. 1.

The construction of Figs. 1, 2, 3 and 4, shows a brush backing 8; brush bristles 9 and 10; an inclined handle 11 including a pair of pins 12 and 13; a securing means including notches in the pins as indicated, a bent metal plate 14 provided with a pair of pin-receiving recesses or apertures 15 overlying and taking about a cut-away part 8' of the backing, and a pivoted locking-piece 16 on the plate 14. Felt buffers 17 may or may not be provided.

The backing 8 is preferably of wood, quite elongated, and of considerable thinness as compared with its width. The backing illustrated, minus the cut-away part 8', and carrying the bristles 9, may be the usual stock article purchasable, as was the one used for my test model, in the ten-cent stores.

Referring to the bristle structure, a feature of the invention is the combination of at least one row, as here, of bristle tufts 9 set in sockets 8" in one of the long faces of the backing, with a plurality of double 90 tufts 10 looped through transverse apertures, as those indicated at 18. This plurality of tufts 10 always includes two terminal outwardly inclined tufts as shown in Fig. 1, to provide enlarged bristle groups projecting 95 beyond the opposite ends of the backing and prolong the bristle spread adequately to increase the extent of sweep and interpose a resilient buffer agent to defeat marring contact of the backing and wood-work adjacent 100 to the area worked over. The axes of the apertures 18 are at right angles to the axes of the sockets 8".

By properly positioning these apertures 18, each of the tufts, or bundles of bristles 10, after being thus 105 looped, may be easily and cheaply secured in the desired spread, by the use of a flexible tying agent 19, preferably a short length of picture-wire, drawn through an adjacent small transverse aperture 20, thence over 110

the looped bristle bundle and thence over the adjacent end of the backing, there being twisted together and tucked in between the down-turned free end lengths of the bristle bundle and under the backing as illustrated. The buffers 17 may then be tacked in place as shown.

The enlarged terminal bristle structures so provided, have also the important advantage of creating pockets at opposite ends and sides of the brush for directing and the better propelling the dust and rubbish in the field of work.

The cut-away part 8' is merely a transverse slot cut through the upper edge of the backing, of the cross-section indicated in broken lines in Fig. 1.

The metal plate 14 is tacked in place to cover this cut-away part 8', and to dispose of its apertures 15, which are circular and of slightly greater diameter than the pins 12 and 13, so that the pins, when set in place for the functioning of the locking piece 16, receive some support from the walls of the slot.

The locking piece 16 is pivoted in place on the plate 14, at the middle of the locking piece and midway between the circular pins receiving apertures 15, so that the piece may be used indiscriminately to secure the handle and backing together, whether the handle is arranged as shown in full lines or reversed as indicated in dotted lines. The locking piece is thus pivoted by a wood-screw 21 (Fig. 3) threaded into the backing below the floor of the slot constituting here the cut-away part 8'.

So that, when the backing and handle are disconnected, the brush may be conveniently hung in the closet, the backing may be provided with one or both of the transverse apertures 22.

The modification of Figs. 5 and 6 is, as will be seen, similar to that of Fig. 1, except for three minor details. First, instead of the cut-away part 8', the cut-away part includes two sockets 8^a registering with the

circular apertures 15 in the plate 14. Second, the plurality of auxiliary tufts 10 comprise, in addition to the terminal, outwardly inclined tufts of Fig. 1, a central vertical tuft 10^a, looped through a transverse aperture 18^a and secured in place and to hold a suitable flare, by means of a tying element 19 passed through two small apertures 20^a. Third, only one of the pins 12 and 13 is notched, and a locking piece 16^a is substituted for the piece 16 of Fig. 1. This locking-piece has only one end functioning as a detent, the other end of the piece being bent over and up as shown to furnish a convenient thumb-plate 16^a. The wood-screw by which this locking-piece is pivotally mounted is threaded into the wooden backing directly under the plate 14, between the sockets 8^a.

The pins 12 and 13 are here the terminal lengths of a single looped wire member 23 (Figs. 1 and 7), the bight of the loop being seated in a transverse slot 11^a cut across an end of the handle 11, a ferrule 24 and the member 23 being anchored in place by a rivet 25 and tack 26 as shown.

I claim:

In a brush, in combination, an elongated backing having a line of sockets formed in one of its long faces with substantially parallel axes, bristle tufts secured in said sockets, the backing also having transverse apertures cut therethrough near the ends of such line with their axes substantially at right angles to the axes of the sockets, and bristle tufts drawn through said apertures and looped and secured in place, with their opposite terminal portions projecting away from said apertures and inclined away from the bristles in the bottom sockets to prolong the bristle-spread beyond the ends of the backing.

In testimony whereof, I have hereunto signed my name on the 27th day of August, 1918.

HENRY A. HAYDEN. [L.S.]
